UNITED STATES PATENT OFFICE.

JAMES O. BUTRICK, OF MUSKEGON, MICHIGAN.

FEED COLLET.

Application filed February 23, 1928. Serial No. 256,346.

This invention relates to feed collets such as are commonly used with automatic screw machines, the purpose of which is to grip, guide and feed the work forward to the tools which 5 operate thereon.

It is an object and purpose of the present invention to provide a feed collet which will frictionally grip the work completely to the outer end of the collet so that there is no 10 waste of material, but all of the material which is being fed by the collet is completely worked up without any short length thereof being wasted; also, to provide an improved adjustable means for such a feed collet.

Various other objects and purposes than those stated will be apparent as an understanding of the invention is had from the following description taken in connection with the accompanying drawings, in which:

Fig. 1 is a side elevation of the collet of my invention.

Fig. 2 is a longitudinal central section therethrough.

Figs. 3 and 4 are transverse sections taken, 25 respectively, on the planes of lines 3-3 and 4-4 of Fig. 2.

Fig. 5 is an end elevation of said collet.

Like reference characters refer to like parts in the different figures of the drawings.

In the construction of the collet, a length of material of cylindrical shape is provided, one end portion or section 1 thereof having a reduced threaded extension 2 and at one end a cylindrical opening 3, bored longitudinally 35 through said extension and through the section 1 nearly to the inner end thereof. The threaded part 2 provides means for attaching the collet to the operating member therefor.

In longitudinal alignment with the section 1 is an integral section 4 having a reduced outside diameter, connected integrally with which is a collar 5 of substantially the same diameter as the section 1 though it may be slightly larger and around which a ring 45 groove 6 is made.

The intermediate section 4 and the adjacent end portions of the section 1 and the collar 5 are longitudinally slotted at a plurality of spaced-apart points, as indicated at 50 7, and are additionally slotted diametrically opposed to make the slots 8. The slots 8 extend entirely through to the outer end of the collar 5 while the slots 7 terminate at their outer ends a short distance inward from the 55 outer ends of the collar 5.

A split ring 9 of spring material is seated

in the groove 6 in collar 5 and its tension acts to force the two halves of the collar at opposite sides of the slot 8 toward each other. Through the section 4 and the collar 5 a longitudinal opening 10 is made preferably 60 hexagonal in cross section.

While the construction has been shown with four slots 7 and two slots 8, it is evident that the number of slots 7 may be varied. In any case the work which is a rod, indicated in dotted outline in Figs. 1 and 3, is fed through the collet and is frictionally gripped by the slotted section 4 of the collet. Wear in the opening 10 in the collar is automatically 65 taken up through the action of the spring ring 9 which causes the two opposed jaws of the collar to grip the work with considerable force. Any wear which may take place in the opening through the intermediate section 70 4 is readily corrected by forcing the various parts between the slots 7 and 8 inward by suitable operations. For instance, the same may be struck with a hammer between the slots at the shoulder between the ends of the two sections 1 and 4, thereby decreasing the cross section area of the opening 10 an amount sufficient to compensate for any wear which occurs.

In the manufacture of this device I produce the same from a solid rod or bar. I bore out the hole at the center and screw thread the inner end and counterbore the same. I then turn down the reduced section at 4 and the recess in the spring collar 9. 80 When this is done, I cut the slots 8, leaving the end complete, and I then cut the slot 7. I then temper or harden the entire collet and thereafter draw the temper of the solid end portion by immersing it in hot lead up to 85 about the point where the section line 4-4 crosses Fig. 2, observing the color and noting the drawing of the temper at the section 4 until it is about half way, and it is quenched while the color indicates that the shoulders 90 between the section 4 and the part 1 are still hard. The heavier parts are thus annealed so that they may be deflected inwardly for the purposes of adjustment. When this is done, I slit the end of the slot 8 by a slitting 105 grinder.

The spring ring 9 is of such dimension as to hold the parts in closed position when they are worn out, and the spring is open at the side as indicated, the spring being the governing means for holding the end jaws yieldingly 110 in position and supplementing the elastic

strips at the section 4. When in use the rod wears the inner section until it fails to operate properly, the same is adjusted for such wear by placing the collet on an anvil and 5 striking a sharp blow with a peening hammer on each one of the sections between the slits 7 at the point where the temper has been drawn. This carries the parts inwardly and the tempered part still yields and serves as 10 the spring, there being of course some resiliency in the annealed parts as well. The sizes of these vary from one-half inch or smaller up to six inches in diameter as at present produced. They can be made even larger or 15 smaller.

The construction of this invention is simple but very effective for the purposes for which it is designed. I have illustrated a practical embodiment of my invention. The 20 invention is not restricted thereto but is to be considered comprehensive of all forms of structure coming within their scope of the claims which define the invention.

I claim:

- 25 1. A device of the class described, comprising an elongated cylindrical body, screw threaded at one end and with an axial bore therethrough with externally reduced diameter portion towards the opposite end forming
- 30 2. A feed collet comprising an elongated tubular body circumferentially closed and screw threaded at one end, the interior of said body being reduced in diameter a considerable part of its length extending inward from the end opposite the screw thread to provide relatively long gripping surfaces, said body also being provided with a plurality of longitudinal slots extending entirely through said gripping surfaces, one or more of said slots extending through the end opposite the screw threaded end, the exterior of said body having a reduced portion and located wholly over said interior reduced portion and spaced from the slotted end and a contracting member applied to the exterior surface of the body surrounding the gripping surface near the slotted end.
- 35 3. A feed collet comprising an elongated tubular body circumferentially closed and screw threaded at one end, the interior of said body being reduced in diameter a considerable part of its length extending inward from the end opposite the screw thread to provide relatively long gripping surfaces, said body also being provided with a plurality of longitudinal slots extending entirely through said gripping surfaces, with a plurality of said slots extending through the end opposite the screw threaded end, the exterior of said body having a reduced portion and located wholly over said interior reduced portion and spaced from the slotted end and a contracting member applied to the exterior surface of the body surrounding the gripping surface near the slotted end.

strips having the temper drawn and the parts thus annealed, whereby the structure is adjustable to wear by forcibly deflecting the annealed portion of said strips inwardly, as specified.

2. A feed collet comprising an elongated tubular body circumferentially closed and screw threaded at one end, the interior of said body being reduced in diameter a considerable part of its length extending inward from the end opposite the screw thread to provide relatively long gripping surfaces, said body also being provided with a plurality of longitudinal slots extending entirely through said gripping surfaces, one or more of said slots extending through the end opposite the screw threaded end, the exterior of said body having a reduced portion and located wholly over said interior reduced portion and spaced from the slotted end and a contracting member applied to the exterior surface of the body surrounding the gripping surface near the slotted end.

3. A feed collet comprising an elongated tubular body circumferentially closed and screw threaded at one end, the interior of said body being reduced in diameter a considerable part of its length extending inward from the end opposite the screw thread to provide relatively long gripping surfaces, said body also being provided with a plurality of longitudinal slots extending entirely through said gripping surfaces, with a plurality of said slots extending through the end opposite the screw threaded end, the exterior of said body having a reduced portion and located wholly over said interior reduced portion and spaced from the slotted end and a contracting member applied to the exterior surface of the body surrounding the gripping surface near the slotted end.

In witness whereof I have hereunto set my hand.

JAMES O. BUTRICK.
